UNITED STATES PATENT OFFICE.

LELAND H. HILL, OF SWISSVALE, PENNSYLVANIA, ASSIGNOR TO WESTINGHOUSE ELECTRIC & MANUFACTURING COMPANY, A CORPORATION OF PENNSYLVANIA.

LIQUID DEOXIDIZER.

Application filed September 10, 1924. Serial No. 736,841.

My invention relates in general to electrical devices having means for deoxidizing the air drawn into such devices and particularly to a liquid deoxidizing seal therefor.

5 One object of my invention is to provide a "breathing" regulator for electrical devices that shall act both as a liquid seal and as a deoxidizing agent.

Another object of my invention is to provide 10 an electrical device having an inert atmosphere confined above the level of an insulating fluid with a liquid seal that also acts as a deoxidizing agent for air drawn into the translating device.

15 In electrical translating devices, such as circuit interrupters and transformers, in which the electrical parts are immersed in an insulating oil, explosions have resulted from the ignition of mixtures of hydrocarbon

20 gases and air in the space above the oil level. In certain constructions, solid deoxidizing agents are placed in the path of air drawn into such devices for the purpose of deoxidizing such air. In such constructions, a "breathing" regulator is also used 25 to control the admission of air in accordance with the pressure inside the translating device.

By means of the present invention, I propose 30 to combine the functions of the "breathing" regulator and the deoxidizing agent into a single unit by employing a liquid having an affinity for oxygen, such as alkali pyrogallol, as the seal for the "breathing" regulator.

The single figure of the accompanying drawing is a view, partially in elevation and partially in section, of an electrical translating device embodying my invention.

40 My invention comprises, in general, an air-tight tank 1 in which an electrical translating device 2, such as a transformer, is immersed in insulating fluid 3, such as oil. Above the oil is trapped an atmosphere 4

45 of inert gas that, in turn, communicates with the outside atmosphere through a liquid seal 5 that also serves as the deoxidizing agent.

The liquid seal 5 is a U-tube 6 attached at one end to the cover member 7 of the electrical device and communicates with the inert gas 4. The other end of the seal 5 is open to the atmosphere. A quantity of

liquid 8 having an affinity for oxygen, such as alkali pyrogallol, is placed in the loop of the seal. A small quantity of liquid 9, such as oil, is placed over the deoxidizing liquid adjacent to the open end of the seal in order to keep the air from reacting upon the alkali pyrogallol when the liquid seal is not transmitting gases. A dehydrating agent 11 may be placed between the container and the deoxidizing agent, if desired.

By reason of the changes in temperature of the transformer 2, the level of the insulating fluid 3 rises and falls, thereby alternately creating pressure and a partial vacuum of the inert gas 4. When the pressure inside the tank reaches predetermined maximum and minimum values, this action is accompanied by corresponding "outbreathing" 70 of gas or "inbreathing" of air through the liquid seal 5. During "outbreathing", the gas bubbles through the deoxidizing liquid 8 and escapes to air without any chemical action taking place.

During the process of "inbreathing", air is drawn through the oil 9 and deoxidizing liquid 8 in the direction of the arrows shown in the drawing. The air bubbling through the alkali pyrogallol, delivers up its oxygen content and accordingly, enters the translating device 1 as an inert and harmless gas, being chiefly nitrogen. The oxygen content of the air that is absorbed in the liquid seal, serves to slightly discolor the alkali pyrogallol but does not form a sludge such as would interfere with the passage of gas through the liquid seal 5. When the deoxidizing fluid becomes sufficiently discolored it may be readily replaced with a new supply at a low cost.

By means of my invention, I have provided a combined "breathing" regulator and deoxidizing agent for containers by employing a liquid having an affinity for oxygen as the sealing element.

I do not wish to be restricted to the specific arrangement of parts herein set forth, as various modifications thereof may be made without departing from the spirit and scope of my invention. For example, I may substitute for the U-tube, the relief valve shown and described in my copending application, Serial No. 608,791, filed December 23, 1922,

(Case No. 10323). I desire, therefore, that only such limitations shall be imposed as are indicated in the appended claims.

I claim as my invention:

- 5 1. In combination, an electrical translating device partially filled with a gas and means comprising a liquid seal having an affinity for oxygen for permitting a transfer of gas between the interior of the translating device and the atmosphere.
- 10 2. In combination, an electrical translating device partially filled with a gas and means comprising a seal of alkali pyrogallol for permitting a transfer of gas between the interior of the translating device and the atmosphere.
- 15 3. In combination, an electrical translating device partially filled with a gas and means comprising a liquid seal having an affinity for oxygen for permitting a transfer of gas between the interior of the translating device and the atmosphere, and a second liquid normally interposed between the first-named liquid and the air.
- 20 4. In combination, an electrical translating device partially filled with a gas and means comprising a seal of alkali pyrogallol for permitting a communication between the

interior of the translating device and the atmosphere, and a second liquid normally interposed between the pyrogallol and the air.

5. In combination, an electrical translating device partially filled with a gas and means comprising a liquid seal capable of excluding oxygen for controlling communication between the interior of the translating device and the atmosphere.

6. In combination, an electrical translating device partially filled with a gas and means comprising a liquid seal capable of forming stable compounds with oxygen for permitting a transfer of gas between the interior of the translating device and the atmosphere.

45 7. In combination, an electrical translating device partially filled with a gas and means comprising a liquid seal capable of extracting oxygen to form a non-gaseous compound with said oxygen for permitting a transfer of gas between the interior of the translating device and the atmosphere.

In testimony whereof, I have hereunto subscribed my name this 4th day of September 1924.

LELAND H. HILL.
